Roeder & Breen*

UNITED STATES PATENT OFFICE.

CARL FRENZEL, OF BROOKLYN, NEW YORK.

DESIGN FOR A CALENDAR.

SPECIFICATION forming part of Design No. 27,807, dated November 2, 1897.

Application filed August 28, 1897. Serial No. 649,888. Term of patent 3½ years.

To all whom it may concern:

Be it known that I, CARL FRENZEL, a citizen of Germany, residing at Brooklyn, county of Kings, and State of New York, have invented and produced a new and original Design for Calendars, of which the following is a specification, reference being had to the accompanying drawing, forming part thereof.

The drawing represents a face view of my newly-designed calendar.

The leading feature of my design consists of a calendar the face-plate of which contains the representation of a bicycle having a segmental field concentric to one of the wheels.

The letter A is the face-plate of a calendar

containing the representation of a bicycle and of a rider *a*, grasping the same. The front wheel *b* is provided with a segmental slot *c* within its rim and with a concentric segmental field *d* beyond the slot, said field having converging transverse partitions *e*. The rear wheel *f* is provided with a sector-shaped slot *g*, as shown.

What I claim is—

The design for a calendar, substantially as herein shown and described.

CARL FRENZEL.
